COMBINED STORAGE CABINET AND DESK

Macy M. Carothers, 328 N. Remington Road,
Columbus, Ohio

Filed May 26, 1959, Ser. No. 56,069

Term of patent 7 years

(Cl. D33—19)

Figure 1 is a front perspective view of a combined storage cabinet and desk showing my design with portions thereof being broken away for convenience of illustration; and

A front perspective view of the cabinet taken from the other side in Figure 2 is the same as that shown, while the back of the article is conventionally plain.

I claim:

The ornamental design for a combined storage cabinet and desk, as shown and described.
